Primary Examiner — Daniel J Domino*Assistant Examiner* — Lee D. Starr(74) *Attorney, Agent, or Firm* — McAndrews Held & Malloy, Ltd.(57) **CLAIM**

The ornamental design for an analyte sensor inserter, as shown and described.

DESCRIPTION

FIG. 1 is a front perspective view of an analyte sensor inserter showing our new design according to a first embodiment; and,

FIG. 2 is a front perspective view of an analyte sensor inserter showing our new design according to a second embodiment.

The dashed broken lines in the figures illustrate portions of the analyte sensor inserter that form no part of the claimed design.
